Application June 14, 1933, Serial No. 675,659

24 Claims. (Cl. 25—30)

This invention relates generally to methods of applying protective coatings like hydraulic concrete to metal piping or cylindrical forms, and to machines useful for carrying out such methods.

It is a general object of the invention to generally improve methods and machines of the above character, to make possible the manufacture of a uniform coating or armor of high protective value at relatively low cost.

A further object of the invention is to provide an improved method of the above character which will make possible a dense and hard protective coating which will be relatively free of objectionable voids.

Another object of the invention is to provide a machine for applying plastic material like hydraulic concrete or hydraulic concrete mortar to a pipe or cylindrical form, which will operate at a relatively high speed, and which will apply a foraminous reinforcement in proper embedded position simultaneously with application of the plastic material.

Further objects of the invention will appear from the following description in which the preferred embodiment of the invention has been set forth in detail in conjunction with the accompanying drawings.

Figure 1 is an end view, illustrating a machine incorporating the present invention.

Fig. 2 is a view similar to Fig. 1, but looking toward the opposite end of the machine.

Fig. 3 is a side elevational view of a portion of the machine shown in Figs. 1 and 2, and illustrating particularly means for vibrating the upper side of the pipe being coated.

Fig. 4 is a side elevational detail, partly in cross section, illustrating the centers for rotatably supporting small pipe or other form being coated.

Fig. 5 is a plan view, illustrating the wrapping of the reinforcing material.

Fig. 6 is a plan view, illustrating the complete machine in operation for the coating of a length of pipe.

Fig. 7 is a plan view, in cross section, illustrating a portion of the carriage which supports certain operating parts of the machine.

Fig. 8 is a side elevational view, partly in cross section, illustrating means for supporting the pipe or other form to be rotated, and to be coated.

Fig. 9 is a side elevational view, partly in cross section, of the continuation of the left side of Fig. 8.

Fig. 10 is a side elevational detail, in cross section, showing the guide structure over which the plastic material passes in its advance upon the pipe or other form being coated.

Fig. 11 is a cross sectional detail taken along the line 11—11 of Fig. 10.

Fig. 12 is an enlarged detail, showing the manner in which the foraminous reinforcement becomes embedded in the layer of plastic material, thru the effects of tension and vibration.

Fig. 12A is a cross section taken along the line 12A—12A of Fig. 12.

Fig. 13 is a cross sectional detail, illustrating perforating means which can be utilized where paper is employed as an outer surfacing.

The method incorporating in the invention can be best understood after a detailed description of the machine illustrated in the drawings. Referring first to the general layout in plan, shown in Fig. 6, the machine consists generally of a pair of structures 10 and 11 for supporting a pipe 12 or other cylindrical form, for axial rotation. Arranged along one side of the pipe 12 there is a carriage 13 adapted to operate along a track 14. The carriage 13 supports various mechanical elements which serve to apply the plastic material to the pipe 12, and may also carry a mixing apparatus 16 for supplying the plastic material in proper condition. It may be explained that while the machine is in operation with the pipe 12 being continuously rotated in one direction, the carriage 13 is moved continuously lengthwise of the pipe, and the plastic material is applied spirally or helicoidally, as illustrated.

Referring now to Figs. 1 and 2, the carriage 13 consists of a suitable frame 17 which can be formed of structural steel members, as shown. The lower portion of this frame carries wheels 18 for operating upon the track 14. Carried by the frame 17, thru certain elements to be presently described, there is a guide structure 19. It is over this guide structure that the plastic material is conveyed, during its application to the pipe 12.

The particular details shown for the guide structure 19 can be explained by reference to Figs. 10 and 11. The principal part of this guide structure is formed by a channel 21 having its flat back side uppermost. In order to operatively support channel 21, a plate 23 underlies its intermediate portion, and the ends of this plate are secured to the depending side channel flanges 24. A stirrup 26 underlies plate 23 and these parts are pivotally connected to

gether by means of a bolt or pin 27. This pivotal connection permits swinging of the channel 21 about a generally upright axis. Stirrup 26 is in turn pivotally connected upon a horizontal axis with a yoke 28. This latter connection is formed by the pivot pins or journals 29, between stirrup 26 and the side upright members 30 of the yoke 28. The attachment between side upright members 30 and the main portion of yoke 28 is preferably adjustable, as by means of bolts 31 which can be engaged in any one of several apertures in the upright members 30. Yoke 28 is in turn adjustably mounted on elements 98 as will be presently explained. It is evident from what has been explained that the support for the channel 21 permits universal movement of this channel with respect to the pipe being coated. In other words this channel can be swung about a generally upright axis at various angles with respect to the axis of rotation of the pipe, or it can be tilted at various angles with respect to the horizontal.

In order to provide means for continuously feeding a layer of plastic material upon the upper surface of the channel 21, I provide a hopper 33, which can be made of sheet metal plates, welded together. This hopper overlies the channel 21, and is preferably positioned substantially co-axial with the axis of pivot pin 27, so that varying amounts of material within the hopper has substantially no effect upon counterbalancing of the channel. For reasons which will be presently apparent it is desirable to retain hopper 33 in its operating position by a hinge connection, so that it can be unlocked and swung to one side. Thus one side of the hopper has been shown connected to one side of the channel 21 by hinge structure 34. The other side of the hopper is adapted to be retained in operating position by releasable locking means which may be formed as follows:—A rod 36 has a pivotal connection 37 with one side of the channel 21. A collar 38 is slidably positioned upon rod 36 and is urged toward the pivotal connection 37 by compression spring 39. Mounted upon the corresponding side of hopper 33, there is a bracket 41, having a lower flange 42 which is slotted to receive rod 36. Upon swinging rod 36 outwardly and downwardly, collar 38 is freed with respect to flange 42, to permit the hopper to be swung to one side about the axis of hinge structure 34. When the hopper is returned to its normal position, rod 36 can be swung upwardly to again engage collar 38 above the slotted flange 42. In this connection it will be noted that the surfaces of collar 38 are so formed, as to permit its automatic engagement with the upper surface of flange 42, when the rod 36 is swung upwardly.

Certain parts associated with the hopper 33 serve to determine the thickness of the coating applied to the pipe. Therefore it is desirable to have this hopper occupy a predetermined position with respect to the channel 21 when it is in its operating position. For this reason spacer elements 44 have been shown interposed between the lower side edges of the hopper 33, and the side edge portions of channel 21. The hopper rests upon these spacer bars or elements, when it is in normal operating position as shown in Fig. 11. Plastic material fed into hopper 33 is fed forwardly over channel 21, towards the pipe to be coated. A smooth surface for the upper side of the channel can be assured by a sheet metal surfacing 46. In order to prevent any

flow of plastic material in the reverse direction, that is underneath the rear lower edge of the hopper, the rear hopper wall 47 is provided with an adjustable gate 48. The lower edge of gate 48 can be adjusted to be in close proximity with the sheet metal surfacing 46 of channel 21, to permit passage of a strip of foraminous reinforcement as will be presently explained, but to prevent extrusion of plastic material.

To provide for the feeding of plastic material from the hopper in a direction towards the pipe, a plate 49 is removably secured to the forward hopper wall 51. The lower portion of plate 49 is provided with a forwardly curved lip portion 52, which overlies the upper surfacing 46 of the channel 21. With this arrangement it is evident that the thickness of spacer elements 44 determines the thickness of the coating applied.

In order to secure a uniform and continuous flow of plastic hydraulic Portland cement or Portland cement mortar from hopper 33, below the lip portion 52, I provide means which serves to subject certain parts to rapid and continuous vibration. Thus mounted upon the forward wall 51 of hopper 33, by way of a bracket 56, there is a pneumatic hammer 57. The operating plunger 58 of this hammer bears upon a bar 59, which in turn rests upon lip portion 52. Since lip 52 is somewhat resilient and has its side edges free with respect to the hopper, it is vibrated in a vertical direction to insure a smooth continuous flow of plastic material from the hopper. In addition the main part of the hopper 33, and particularly the rear wall 47, is subjected to continuous vibration by means of an additional pneumatic hammer 61.

During its movement from the hopper to the pipe, the layer of plastic material fed from the hopper is conveyed along by a strip of suitable material, such as a strip 62 of wire screening, or like foraminous metal reinforcement. As is evident from Fig. 10, this strip of reinforcement passes beneath the lower edge of gate 48 and is therefore substantially flat upon the upper surfacing 46 of channel 21 as it passes beneath the hopper toward the pipe. The mounting for the reel supplying this reinforcement will be explained in the subsequent part of the present detailed description. However, at this point it may be explained that the reinforcement is preferably placed under tension, and is flattened before it is passed beneath hopper 33. Thus, referring to Fig. 10, the reinforcing strip 62 is shown passed beneath a roller 63 fixed to the side brackets 64. From roller 63 the reinforcement passes over roller 66 and fixed roller 67, before it passes beneath the hopper 33. Rollers 66 and 67 are carried by the side brackets 68, and roller 66 is adjustable by hand screws 69. The manipulation of screws 69 makes it possible to keep the reinforcing strip from becoming narrow; that is, it enables an operator to keep one side of the strip from advancing ahead of the other side. In the event the reinforcement tends to advance too rapidly on one side, the screw 69 on that side is turned down to force that end of the roller 66 against roller 67, thus causing sufficient friction on roller 67 to allow the retarded side of the reinforcement to catch up.

It will be noted from Fig. 10 that channel 21 terminates short of the pipe to be coated, and that immediately underlying the pipe there is an extension plate 71. The upper surface of

this plate is substantially coplanar with the upper surfacing 46 of channel 21, and interposed between the forward end edge of channel 21, and adjacent edge of plate 71, there is a lateral slot 72. Plate 71 is fixed to side structural members 73, which in turn are secured to the side flanges 24 of channel 21. For reasons which will be subsequently explained, plate 71 is preferably vibrated rapidly in a vertical direction. For this purpose I have shown pneumatic hammer 74 mounted upon structural members 73, beneath the plate 71. The operating plunger 76 for this hammer engages a cross-bar 77, which in turn engages the under side of plate 71. In order to confine the layer of plastic material during its movement from hopper 33 to plate 71, side guide strips 75 are mounted upon the edge portions of channel 21 (Fig. 10).

During operation of the machine it is desirable to have plate 71 yieldably urged upwardly against the lower side of the pipe, but under varying conditions of operation, it is desirable to adjust the amount of this force. To enable such adjustments there is shown a cross-bar 78 secured to structural members 73, and upon which various counterbalancing weights 79 can be disposed. An increased amount of weight applied to cross-bar 78, obviously tends to reduce the force normally urging plate 71 upwardly against the lower side of the pipe.

Simultaneously with the application of plastic material and foraminous reinforcement to the pipe, it is desirable to apply an outer surfacing material. Good results have been secured by utilizing ordinary cotton cheesecloth, although paper can be employed if desired. Thus referring to Fig. 10, there is shown a strip 81 of cheesecloth, which is supplied from a reel to be presently described. As this strip comes from the supply reel, it is passed between a pair of parallel bars 82, to remove wrinkles and the like. From bars 82, the cloth strip passes over a guide plate 83, which is carried upon the under side of channel 21. Upon leaving the forward end of guide plate 83, the cloth strip is passed over a roller 84, and from thence is passed upwardly thru slot 72, to the upper side of plate 71.

In the event paper is employed in place of cloth, it is desirable to provide the paper with perforations to permit extrusion of water and to facilitate subsequent curing. This can be accomplished by the attachment illustrated in detail in Fig. 13. In this case, in place of passing the paper between the bars 82, the paper is passed between a pair of perforating rolls 86 and 87, which are carried by the rear end of channel 21. After being perforated, the paper passes over the guide plate 83, and eventually thru the slot 72 upon the upper side of plate 71, as has been previously described for application of cloth surfacing.

Referring now to Fig. 1, it will be noted that the foraminous metal reinforcement 62 is supplied from a reel 91, and the surfacing strip 81 supplied from a reel 92. These reels are rotatably carried by brackets 93 and 94, which in turn are carried by the upright structural members 96 of a sub-frame 97. The horizontal structural elements 98 of sub-frame 97 are disposed upon the lower platform 99 of the carriage frame 17. Referring to Fig. 11 it will be noted that yoke 28 is mounted upon the structural elements 98, and that the sub-frame as a whole at this point is pivotally connected to the

lower platform 99, by means of pivot pin 101. This pivotal connection permits general adjustment of the sub-frame 97 about a vertical axis aligned with the axis of pivot pins 29, so as to enable a general alignment of the reels 91 and 92 with respect to the entire guide structure 19. When the sub-frame 97 is adjusted to a proper position with respect to guide structure 19, it is clamped in such adjusted position to the lower platform 99. For this purpose Fig. 7 shows a portion of the platform 99 provided with a series of holes 103, which can receive clamping bolts.

During certain times, as for example in setting the machine up for operation, it is desirable to raise the outer end of guide structure 19 upon a relatively fixed rest. Thus referring to Fig. 10, a rod 106 has been shown eccentrically pivoted to the upright members 96 of the sub-frame 97. When this rod is swung upwardly it serves as a rest for the guide structure 19, as shown in Fig. 1. However when swung downwardly as shown in Fig. 10, it is disengaged with respect to the guide structure.

Referring to Fig. 1, it will be noted that the sides of channel 21, for that portion of the channel lying between the uprights 96, are provided with side rollers 107. These rollers serve to engage the inner opposed faces of uprights 96, thereby limiting lateral movements of the channel, but permitting movements in a vertical direction with a minimum of resistance.

A suitable arrangement for supporting large sized pipes to be coated is shown in Figs. 8 and 9. In this case a rotatable shaft 111 is carried by the journals 112. The journals are in turn suitably supported upon a base 113, which can be formed of a pair of rails. An expandable chuck 114 is fixed to shaft 111 and serves to engage one end portion of the pipe 12. Arranged below shaft 111, there is a countershaft 115, adapted to be driven by a motor 116 (Fig. 2) thru the change speed gear sets 117 and 118, and the gear box 119. Pinion 121 is splined to shaft 115, and engages with a gear 122 fixed to shaft 111. To secure a different drive ratio, another pinion 123 is likewise splined to a shaft 115, and is adapted to engage a gear 124 fixed to shaft 111. A suitable clutch 126 is interposed between the connection from gear box 119 and shaft 115, to disrupt the drive connection if desired.

The other end of the pipe 12 is engaged by an expandable chuck 128 which in turn is rotatably secured to one end of a longitudinally slidabile plunger 129. Plunger 129 is splined in the standard 131 and extends through a stationary, hydraulic cylinder 132. A piston 133 operates within cylinder 132, and is fixed to the plunger 129. The parts just described are supported upon a carriage 134, which is provided with wheels to operate upon the rails 113. Hydraulic pressure for operating piston 133 can be provided by a gear pump 136, driven by an electric motor 137. The hydraulic circuits connected to gear pump 136, can include a surge tank 138.

In order to afford means for quickly shifting carriage 134 longitudinally of the rails 113, I have shown a hydraulic or pneumatic cylinder 139, which is mounted upon the carriage 134. Within the cylinder 139 there is a piston 141, connected to a piston rod 142. The outer end of piston rod 142 is anchored to an abutment 143, which is fixed to the rails 113. By selectively introducing compressed air or liquid under pressure to the ends of cylinder 139, the carriage 150

134 can be moved along the rails 113 to a desired position.

Fig. 4 illustrates an arrangement which can be employed when relatively small pipe is to be coated. In this case, in place of utilizing expandable chucks engaging the ends of the pipe, the ends of the small pipe 146 are engaged by the centers 147 and 148. These centers are preferably of substantially the same external diameter as the external diameter of the pipe to be coated, whereby the coating can be commenced upon the one center, say center 147, and terminated upon the other center 148.

As has been previously stated, during a coating operation the carriage 13 and the parts which it supports is moved along the track 14 at a speed bearing a definite ratio to the speed of rotation of the parts. Thus a drive connection to the carriage is illustrated as follows:—Mounted upon the shaft 111 (Figs. 2 and 8) there is an expandable pulley 151. Mounted within the base 113 there is a rotatable shaft 152, carrying a pulley 153. Pulleys 151 and 153 are connected by cables 154, which are maintained tensioned by the idler pulley 156. Extending laterally of the track 14, there is a shaft 157, which is driven from shaft 152 thru bevel gears 158. The end of shaft 157 which terminates between the rails of track 14 (Fig. 2) carries a sprocket 159, which is engaged by one end of an endless chain 161. Chain 161 extends the full length of movement of carriage 13, and its other end engages the idler sprocket 162. Underlying the main carriage 13 (Fig. 1) there is a guide channel 163 thru which the upper run of the chain extends. Mounted upon the carriage 13 there is a suitable mechanism, under the control of the operator whereby the upper run of the chain can be locked to the carriage, to drive the same. This locking means need not be described in detail, as its construction will be apparent to those skilled in the art.

After coating a section of pipe it is desirable to provide means for quickly returning carriage 13 to its initial position. For this purpose I have shown a suitable motor 171 (Fig. 7), which may operate from pneumatic pressure, and which is adapted to drive the axle for one or more of the wheels of the carriage, thru a chain connection 172, and clutch 173.

In order to maintain an adequate charge of plastic material within the hopper 33, during a coating operation, it is desirable to provide a mixing apparatus 16 upon the carriage 13. The details of this mixing apparatus need not be described, as many apparatuses of this character which will operate satisfactorily are known upon the market. However it may be explained that the hydraulic plastic mix prepared in this apparatus is discharged thru a launder 178 to the hopper 33 as shown in Fig. 1. The gate 179, controlling the discharge of the plastic mix, can be operated to effect opening and closing of the same, by the hydraulic or pneumatic cylinder 181.

To secure a denser final coating it has been found desirable to apply vibration to the plastic coating along the upper side of the pipe. For this purpose I have shown a plate 186 (Fig. 3) supported by a bracket 187, through the parallel motion links 188 and 189. A pneumatic vibrator 191 is attached to plate 186 to rapidly vibrate the same in a vertical direction. During operation of the machine plate 186 rides upon the

coating immediately after its application, whereby all of the plastic material applied passes beneath the same and thereby is subjected to vibration. When the machine is not operating, plate 186 can be retained in an elevated position 8 by latch 192, which is adapted to engage pin 193.

Operation of my machine is as follows:—The machine is initially set up and adjusted to secure the thickness of coating desired, and to insure proper operation consistent with diameter of the pipe being coated. In this connection the subframe 97 must be so adjusted that the angularity of guide structure 19 with respect to the axis of the pipe, will apply the material to the 9 pipe with the proper pitch. The metal reinforcing 62 and the cloth strip 81 are properly threaded with respect to the guide structure 19, and the ends of these strips are then secured to that end of the pipe 12 at which the 91 coating is to be started. A proper plastic mix prepared in the mixing apparatus 16, and a charge of this mix is then introduced into the hopper 33. The various pneumatic hammers and vibrators are now put into operation, and 98 rotation of the pipe is commenced, with simultaneous synchronized movement of the carriage 13 longitudinally of the pipe. As the strip of foraminous reinforcement progresses beneath 105 hopper 33, a layer of the plastic mix is applied 101 to the same, for substantially the full width of the reinforcement, and this layer of plastic material is then conveyed together with the reinforcement. In other words the reinforcing strip serves as a conveying medium for the layer of 110 plastic material fed from the hopper. As the reinforcement progresses over plate 71, the cloth strip 81 is applied to the under side of the same, to be simultaneously wrapped upon the pipe. As has been previously explained the foraminous reinforcement is under tension as it is applied to the pipe. The rapid vertical vibration of plate 71 serves to repeatedly pound the layer of plastic material and likewise the accompanying reinforcement, against the lower 115 side of the pipe, adjacent to or at the region of initial contact with the pipe surface. The effect of such combined tension and vibration upon the reinforcement, causes the reinforcement to embed itself to an intermediate depth 120 in the layer of plastic material. This can best be explained by reference to Figs. 12 and 12A. As illustrated in these figures the foraminous reinforcement 62 is gradually embedding itself 125 into the layer 9 of plastic material, as the reinforcement progresses along the upper side of plate 71. It has been found that with a Portland cement mix containing sand, and possibly somewhat coarser aggregate material such as fine gravel, the metal screening forming the reinforcing strip will embed itself to an intermediate depth, but will not become embedded sufficiently for it to contact with the outer surface of the pipe. At this point it may be explained that the reinforcement, in order to be effective, 130 must be embedded to an intermediate depth in the layer of plastic material applied to the pipe. If it is applied directly to the outer surface of the pipe, then it will not properly perform its desired reinforcing function. Likewise if it is permitted to occupy a position adjacent the outer surface of the plastic layer, and then it will not properly reinforce the coating, and it will be exposed to corrosion.

In further explanation of the manner in which 150

the reinforcement is embedded in the plastic material, as explained with respect to Figs. 12 and 12A, it should be noted that embedding movement of the foraminous reinforcement necessarily is accompanied by extrusion of the plastic material thru the apertures in the reinforcement. Ordinarily extruded plastic material would not form a smooth outer layer portion over the reinforcement, unless troweled. 10 However application of the cloth strip 81 over the plate 71 together with vibration makes a troweling operation unnecessary. Thus it will be noted that while the plastic material is extruding thru the foraminous reinforcement, it is being confined by the cloth strip, which is under a certain degree of tension, and such confinement of the plastic material, accompanied by the vibration to which the plastic material is being subjected by plate 71, effectively compacts the extruded plastic material to form a dense outer layer portion. Use of the cloth strip also makes possible application of the coating material at relatively high speed, because the cloth prevents throwing off of the plastic material by centrifugal force. 25

Plate 71 also assists in forming an effective junction between successive convolutions of the plastic material as this material is supplied. Thus referring to Figs. 5 and 12A, it will be seen that the pitch at which the reinforcement is applied together with the plastic material, is such as to cause adjacent edges of the reinforcement to overlap. Since the layer of plastic material is applied to substantially the full width of the reinforcement, there is also an overlap with respect to the adjacent edges of the plastic material applied. Plate 71, due to the rapid vibration to which it is subjected, effectively pounds down this overlap, so that the resulting coating is of substantially uniform thickness. Not only does this overlap provide a relatively strong junction between successive convolutions but likewise these junctions are rendered relatively free of voids, due to the surplus plastic material utilized in these regions and the pounding down of the same. It will also be noted from Figs. 5 and 12A that as the cloth 30 35 40 45 50 55 60 65 70 75 80 85 90 95 100 105 110 115 120 125 130 135 140 145 150

is squeezed from the hydraulic plastic material, due to the pounding to which it is subjected and to the tension of the cloth surfacing. Although it is desirable to resort to hydraulic curing to insure proper strength and hardness, squeezing out of excess water at this time aids in securing a highly densified coating. 80

After the machine has operated to apply the coating to one section of the pipe, further operation is discontinued, and the metal and cloth strips are cut. This coated section is now removed from the machine and a new pipe applied in position to be coated. The carriage 13 is returned to the other end of the pipe and the operations described above are repeated. 85 90 After the concrete has set, the ends of the pipe can be trimmed in any desired manner.

The present specification is a continuation in part of subject matter disclosed in my co-pending applications Serial Nos. 494,822 and 537,009, filed November 10, 1930 and May 13, 1931, respectively.

I claim:

1. In a method of applying a layer of hydraulic plastic material to a form, the steps of continuously applying a layer of the plastic material upon a strip of foraminous metal reinforcement, wrapping the strip spirally about the form, and applying vibration and tension to the reinforcement as it is applied to cause it to embed itself to an intermediate depth in the layer of plastic material. 100

2. In a method of applying a layer of hydraulic plastic material to a form, the steps of continuously applying a layer of the plastic material upon a strip of foraminous metal reinforcement, wrapping the strip spirally about the form, simultaneously wrapping a strip of covering material upon the form upon top of the plastic material and the foraminous reinforcement, and applying vibration and tension to the reinforcement as it is applied to cause it to embed itself to an intermediate depth in the layer of plastic material. 110

3. In a method of applying a layer of hydraulic plastic material to a form, rotating the form about its axis, continuously supplying a layer of the plastic material upon a strip of foraminous metal reinforcement, wrapping the strip spirally about the form with the strip together with the plastic material advancing towards the lower side of the form, simultaneously applying a strip of outer surfacing material upon the under side of the metal reinforcement as this reinforcement is advanced toward the form, and then applying vibration and tension to the reinforcement as it is applied to the form to cause it to embed itself to an intermediate depth in the layer of plastic material. 120 125

4. In a method of applying a layer of hydraulic plastic material to a form, the steps of rotating the form about its axis, continuously supplying a layer of the plastic material upon a strip of foraminous metal reinforcement, wrapping the strip together with the layer of plastic material spirally upon the form, with the reinforcement being advanced toward the under side of the form, simultaneously applying a strip of surfacing material spirally about the form, with the strip of surfacing material being advanced upon the form upon the under side of the foraminous reinforcement as this reinforcement is being applied to the form, applying tension to the foraminous reinforcement and applying vibration to the reinforcement and the 130 135 140 145 150

75 During a coating operation considerable water

- plastic material as it is being applied to the form, whereby the reinforcement is caused to embed itself to an intermediate depth in the layer of plastic material, and whereby that portion of the plastic which material is caused to assume a position overlapping the foraminous reinforcement is made relatively compact.
5. In a method of applying a layer of hydraulic plastic material to a form, the steps of rotating the form about its axis, advancing a layer of the plastic material to the under-side of the form whereby the layer is wrapped spirally upon the form, rapidly pounding the plastic material near the region where it is being applied to the under side of the form, and then rapidly pounding the applied layer adjacent the upper side of the form, thereby causing removal of air bubbles.
6. In a method of applying a layer of hydraulic plastic material to a form, the steps of rotating the form about its axis, wrapping a strip of foraminous reinforcement spirally about the form, causing the metal reinforcement to be applied to the form together with a layer of the plastic material extending for substantially the full width of the reinforcing strip, causing a substantial overlap between adjacent edge portions of the reinforcing strip and of the plastic material applied together with the same, upon the form, and rapidly pounding the regions of said overlap to produce a resultant coating of substantially uniform thickness.
7. In a method of applying a layer of hydraulic plastic material to a form, the steps of rotating the form about its axis, advancing towards the lower side of the form, a strip of foraminous reinforcement, a strip of surfacing material underlying the foraminous reinforcement, and a layer of the plastic material upon the foraminous reinforcement and extending for substantially the entire width of the reinforcement, causing the foraminous reinforcement, together with a strip of surfacing material, and the plastic material, to be wrapped spirally about the form, with adjacent edges of the foraminous reinforcement overlapping, causing the strip of surfacing material to be likewise applied with overlapping edge portions adjacent the region of the overlap between the edge portions of the foraminous reinforcement, applying tension to the reinforcement as it is applied upon the form, then applying rapid pounding to the plastic material applied to the form before hardening of the same, to reduce the thickness of the coating along the region of the overlap and to cause the reinforcement to embed itself to an intermediate depth in the layer of plastic material.
8. In a method of applying a layer of hydraulic plastic material to a form, the steps of continuously rotating the form, continuously advancing a strip of material to the form whereby the strip is wrapped spirally about the form, and continuously squeezing excess water from the plastic material as it is applied.
9. In a method of coating a pipe or like form, advancing superposed strips of foraminous reinforcement and surfacing material toward the form, with the surfacing outermost, causing these strips to be wrapped spirally upon the form, applying a layer of plastic material upon the inner side of the reinforcing strip, and then causing the reinforcing strip to embed itself into the layer of plastic material while simultaneously compacting that portion of the plastic material which is extruded thru the reinforcing strip.
10. In a machine of the character described, means for supporting and rotating a pipe or other form to be coated, a hopper adapted to receive a mass of hydraulic plastic material and having a lower discharge opening, means for guiding a foraminous strip beneath said opening, whereby plastic concrete fed thru said opening is deposited upon said strip, means for applying tension to the foraminous strip as this strip together with the plastic material, is applied spirally about the form, and means for applying vibration whereby during application of the strip to the form it is caused to embed itself to an intermediate depth in the layer of plastic material.
11. In a pipe coating machine, means for supporting and rotating a form to be coated, a hopper adapted to receive a mass of hydraulic plastic material and having a lower discharge opening, means for guiding a strip of foraminous reinforcement beneath said opening, whereby concrete fed thru said opening is deposited upon said strip, means for progressing the hopper and guide means longitudinally of the pipe, whereby the strip of reinforcement together with the layer of plastic material carried by the same, is wound spirally upon the pipe, means for repeatedly pounding the coating as it is applied to the under side of the pipe, and means overlying the pipe for repeatedly vibrating the coating, before setting of said plastic material.
12. In a machine of the character described, means for supporting and rotating a form to be coated, a framework disposed alongside the form, means for progressing the framework longitudinally of the axis of rotation of the form, a guide structure movably carried by the framework and normally disposed at an angle to the axis of the form, said structure having a substantially flat bottom and having its one end terminating adjacent the lower side of the form, said guide structure being adapted to receive a strip of foraminous reinforcement to be wound spirally about the pipe, means for feeding said strip into said guide structure and for tensioning the same, a hopper carried by the frame above the guide structure and adapted to receive hydraulic plastic material, said hopper having a lower discharge opening overlying said guide structure and of a width substantially the same as that of the guide structure, a plate underlying the form and serving as an extension of said guide structure, and means for feeding a strip of surfacing material over the upper surface of said plate and beneath said reinforcement.
13. In a machine of the character described, a guide structure over which a layer of hydraulic plastic material may pass to be applied helically upon a pipe or like form, a hopper overlying said structure to receive a charge of said material, means for feeding a conveying strip beneath said hopper and over said structure, a resilient lip formed upon the hopper beneath which the plastic material may flow, and means for rapidly vibrating said lip.
14. In a method of coating pipes or like forms with concrete, the steps of applying a layer of concrete in plastic form upon a strip of foraminous metal reinforcement, wrapping the strip about the pipe with the concrete between the outer surface of the pipe and the reinforcement, and applying vibration and tension to the

reinforcement to cause it to embed itself into the layer of concrete.

15. In a method of coating pipes or like forms with concrete, the steps of applying a layer of the concrete in plastic form upon a strip of foraminous metal reinforcement, wrapping the strip about the pipe with the concrete between the outer surface of the pipe and the reinforcement, applying vibration and tension to the reinforcement to cause it to embed itself into the layer of concrete, and then smoothing over the concrete thereby extruded thru the perforations of the reinforcement.

16. In apparatus for coating pipes or like forms, means for wrapping a strip of foraminous metal reinforcement helicoidally about a pipe, means for applying a layer of plastic concrete upon one side of the reinforcement whereby the layer is wound upon the pipe together with the reinforcement, means for applying tension and vibration to the reinforcement, to cause it to embed itself into the layer of concrete on the pipe, and means for smoothing over the concrete thereby extruded thru the perforations of the reinforcement.

17. In a method of coating pipes or like forms with plastic material, the steps of applying a layer of plastic material upon a strip of foraminous metal reinforcement which is relatively narrow compared to the length of the pipe, wrapping the strip together with the plastic layer helicoidally upon the pipe, tensioning the reinforcement and tamping the plastic material together with the reinforcement as it is applied to the pipe to cause the reinforcement to embed itself in the plastic material, thereby forming both outer and inner layer portions of plastic material on the sides of the reinforcement without further application of plastic material, and compacting the outer layer portion to form an uninterrupted covering for the reinforcement.

18. In a process of the character described, the steps of continuously forming a layer of plastic concrete from a mass of the same, continuously conveying said layer away from the mass and wrapping the same about a form, and rapidly pounding the layer immediately upon contacting the same with the form.

19. In a process of the character described, the steps of continuously forming a layer of plastic concrete from a mass of the same, continuously conveying said layer away from the mass and wrapping the same spirally about a pipe or like form, and continuously vibrating the layer prior to contacting the same with the pipe.

20. In a method of the character described,

the steps of rotating a pipe or like form to be coated, applying a layer of plastic concrete spirally to the pipe in such a manner as to overlap successive convolutions, and tamping the concrete after application to produce a substantially uniform coating.

21. In a method of the character described, advancing a strip of foraminous metal reinforcement toward a pipe or like form and causing the same to wrap upon the pipe spirally, continually supplying concrete to said strip while the strip is advancing toward the pipe, causing said concrete to be distributed to cover both sides of said strip, and utilizing said strip as a conveying medium to carry the concrete upon the pipe to form a continuous reinforced coating.

22. In a method of the character described, the steps of rotating a pipe or like form to be coated, advancing a strip of foraminous metal reinforcement toward the pipe and causing the same to wrap upon the pipe spirally, continually supplying concrete to one side of said strip while the strip is advancing toward the pipe, causing said concrete to be distributed to cover both sides of said strip, and utilizing said strip as a conveying medium to carry the concrete upon the pipe to form a continuous reinforced coating.

23. In a method of the character described, the steps of rotating a pipe or like form to be coated, continuously advancing a strip of foraminous metal reinforcement toward the pipe and causing the strip to wrap upon the pipe spirally, continually delivering plastic concrete to one side of the strip while the strip is advancing toward the pipe, causing the concrete to be distributed to cover both sides of the strip, and applying a covering strip upon the pipe simultaneously with the reinforcing strip and the concrete carried by the same, said latter strip being likewise wound spirally and applied on the outer surface of the concrete.

24. In a method of the character described, the steps of rotating a pipe or like form to be coated, continuously advancing a strip of foraminous metal reinforcement toward the pipe and causing the strip to wrap upon the pipe spirally, continually delivering plastic concrete to one side of the strip while the strip is advancing toward the pipe, causing the concrete to be distributed to cover both sides of the strip, and applying a cloth strip upon the pipe simultaneously with application of the reinforcement strip and the concrete, said cloth strip being likewise wound spirally and applied on the outer surface of the concrete under tension.
